UNITED STATES PATENT OFFICE.

LUCIUS H. PRINDLE, OF NEW BRITAIN, CONNECTICUT, ASSIGNOR TO THE NORTH & JUDD MANUFACTURING COMPANY, OF SAME PLACE.

DESIGN FOR A SNAP-HOOK.

SPECIFICATION forming part of Design No. 27,751, dated October 19, 1897.

Application filed August 26, 1897. Serial No. 649,650. Term of patent 14 years.

To all whom it may concern:

Be it known that I, LUCIUS H. PRINDLE, a citizen of the United States, residing at New Britain, county of Hartford, and State of Connecticut, have invented a certain new and original Design for Snap-Hooks, of which the following is a full, clear, and exact description.

My invention is illustrated by the accompanying drawing, which shows in perspective a snap-hook containing my new and original design.

The leading feature of my design is the representation, on the side of the body portion A of a snap-hook, of a half-diamond B and a full diamond C, the latter touching the point of the half-diamond B and arranged in line therewith, substantially as shown. The sides of the half-diamond B at its broadest point merge into the end of the loop D, which is shown as connected to the rear end of the body portion A. As the body portion A tapers from its rear end toward the bend E of the hook it is desirable that the size of the ornaments B and C be made to correspond somewhat therewith, so as to give a symmetrical effect. Ornamentations corresponding to B and C are provided on the opposite side of the shank A, but are not visible in the drawing owing to the angle at which the drawing is viewed.

What I claim is—

The design for a snap-hook herein shown and described.

Signed at New Britain, in the county of Hartford and State of Connecticut, this 19th day of August, 1897.

LUCIUS H. PRINDLE.
